United States Patent Office

Des. 228,372

Patented Sept. 18, 1973

228,372

MOBILE BOOTH

Richard C. Bue and Kermit H. Wilson, Minneapolis, Minn.; said Bue assignor to Sico Incorporated, Minneapolis, Minn.

Filed Jan. 31, 1972, Ser. No. 222,453

Term of patent 14 years

Int. Cl. D6—02

U.S. Cl. D6—59

FIG. 1 is a view in perspective as seen from the front and one side of a mobile booth showing our new design;

FIG. 2 is a view in top plan;

FIG. 3 is an elevational view of the front side thereof;

FIG. 4 is an elevational view of the rear side thereof;

FIG. 5 is an elevational view of one end thereof; and

FIG. 6 is an elevational view of the opposite end thereof.

The bottom, which is not shown, is devoid of ornamentation.

We claim:

The ornamental design for a mobile booth, as shown and described.
